ACOUSTIC SOUND-ATTENUATING PANELS

BACKGROUND OF THE INVENTION

The present invention relates to a sound-attenuating panel intended to be applied to a wall of an enclosure for the purpose of reducing the propagation of sonic or ultrasonic pressure waves. This panel can, for example, be fixed on a wall or on the ceiling of a tunnel, the entrance to a staircase or of a room.

SUMMARY OF THE INVENTION

The panel according to the invention is characterized in that it comprises a base provided with fins which are perpendicular to it, the whole being made of an elastomer material.

The fins may be orientated in one direction only but they are, preferably, disposed in two different directions.

These fins may be continuous or may be interrupted.

BRIEF DESCRIPTION OF THE DRAWING

FIG. 1 is a fragmentary elevational view of a portion of a first embodiment;

FIG. 2 is a section on the line II-II of FIG. 1;

FIG. 3 and 4 show, to a larger scale, one cell of the panel and indicate the paths of a bundle of sound waves;

FIG. 5 is a view similar to FIG. 1 of second embodiment; and

FIG. 6 is a view similar to FIG. 1 of a third embodiment.

DESCRIPTION OF THE PREFERRED EMBODIMENTS

In the embodiment of FIGS. 1 and 2, the sound-attenuating panel is constituted by a plane base 1 which is fixed on to wall 5, and by a plurality of parallel fins 2. The latter have their planes perpendicular to that of the base 1 and are integral with the latter, the assembly being made of an elastomer material and manufactured, for example, by moulding or vacuum forming.

As it can be seen in FIG. 3, a sound wave bundle 3 which impinges upon the panel and of which the direction is inclined with respect to the plane of the base 1, is reflected by this base, which partially attenuates it. A part of the bundle leaves as indicated at 3a in a direction symmetric to the incident direction with respect to a perpendicular to the base 1, while another part of the bundle undergoes a second reflection on one of the fins 2 and leaves as indicated at 3b in the direction of the incident wave bundle.

If the sound wave bundle is sufficiently inclined in relation to the base 1 or if the fins are sufficiently high in relation to the distance which separates them, the sound bundle may undergo several reflections which give rise, in each case, to a supplementary attenuation of the sound level. Thus, for example, in FIG. 4 there is indicated diagrammatically at 4 a sound bundle and it will be noted that the latter undergoes seven reflections before leaving the panel. If the amount of attenuation is, for example, about 0.8 at each reflection, the sound bundle leaves the panel with an intensity which is equal to 0.21 times that of the incident bundle.

The panel according to the invention thus ensures a substantial reduction in the sound level, while only a part of the incident bundle is reflected on itself. The bundle may undergo

several reflections, thus suffering each time an attenuation, before leaving the screen.

More precisely, if θ denotes the inclination of the sound bundle with respect to a perpendicular to the base 1, m is the distance between two adjacent fins and p is the height of a fin, it can be established that the edge of the bundle meeting the end of a fin undergoes:

one reflection if $0 < \theta < \theta_1$, where $\tan \theta_1 = m/p$

two reflections if $\theta_1 < \theta < \theta_2$, where $\tan \theta_2 = m/p$

three reflections if $\theta_2 < \theta < \theta_3$, where $\tan \theta_3 = 3m/12p$

n reflections if $\theta_{n-1} < \theta < \theta_n$, where $\tan \theta_n = nm/12p$

It is thus to advantage if the height p is relatively large and the distance m relatively small; if the value of m is nevertheless limited by the fact that each fin has a thickness e which is not zero and that only the surface of the panel comprised within the interior of the fins is effective, the panel having thus an efficiency equal to $1 - 2(e/m)$.

In practice, it is preferable to select m between 3 and 16 millimeters and p between 3 and 20 millimeters.

The embodiment of FIGS. 1 and 2 is only effective in practice if the main direction of the propagation of the sound wave lies in a plane perpendicular to the fins, such as the plane of section II-II. In effect, if this direction is, for example, in a plane parallel to the fins, the sound bundle is subjected only to a single reflection against the face of the base 1 and will only be relatively slightly attenuated.

As a result, if the sound source is movable, it is to advantage to provide fins 2a orientated in a first direction and fins 2b orientated in a direction perpendicular to the first, as in the embodiment of FIG. 5. The panel is thus effective, whatever the direction of the sound source.

In the embodiment of FIG. 6, there are provided not only the fins 2a, 2b orientated in two perpendicular directions, but additionally fins 2c and 2d disposed along diagonals of the squares formed by the fins 2a, 2b. This arrangement allows for a number of reflections of the sound bundle equal to that which will be obtained with the fins 2a and 2b alone and limited one with respect to the other by a somewhat smaller distance, but with a smaller quantity of material and an improved efficiency, the active surface of the panel being larger.

Moreover, in this embodiment, the fins are interrupted, at the zone where the fins 2a, 2b, 2c and 2d must intersect in such a manner that they are more flexible and enable a better attenuation. Moreover, the different cells defined by the fins 45 communicating between themselves, allows for example, when the panel is vertical, for moisture which may be introduced into a cell to flow downwardly towards the base of the screen.

I claim:

50. 1. A sound-attenuating panel of elastomeric material comprising a base, a first set of parallel fins projecting perpendicularly from the base, a second set of parallel fins projecting perpendicularly from the base, said first set of fins extending transversely to said second set of fins to define therewith a plurality of cells of quadrilateral cross section and a respective further fin projecting from the base and extending diagonally across each said cell between one pair of opposed corner portions of said cell, said first and second sets of fins being interrupted in the region of the said opposed corner portions of said cells.

55. 2. A panel according to claim 1 wherein said first set of fins extends perpendicularly to said second set of fins.
